UNITED STATES PATENT OFFICE.

DAVID M. PERINE, OF NEW YORK, N. Y.

SAFETY-RAZOR.

1,127,505.

Specification of Letters Patent.

Patented Feb. 9, 1915.

Application filed January 6, 1914. Serial No. 810,598.

To all whom it may concern:

Be it known that I, DAVID M. PERINE, a citizen of the United States of America, residing in the city, county, and State of New York, have invented certain new and useful Improvements in Safety-Razors, of which the following is a true and exact description, reference being had to the accompanying drawings, which form a part thereof.

10 My present invention consists in an improved safety razor, devised with the object of providing an effective blade holder of simple and inexpensive construction, and adapted to be stamped out of sheet metal, 15 and a thin double edged blade cut away to receive blade positioning parts carried by the holder in a manner not tending to the formation of cracks or flaws in the blade in the manufacturing and tempering of the 20 latter.

The various features of novelty which characterize my invention are pointed out with particularity in the claims annexed to and forming a part of this specification. 25 For a better understanding of the invention, however, and of the advantages possessed by it, reference should be had to the accompanying drawings and descriptive matter in which I have illustrated and described one 30 form in which my invention may be embodied.

Of the drawings: Figure 1 is a plan view of a sheet metal blank from which the body of the holder may be made; Fig. 2 is a plan 35 view of the sheet metal blank from which the blade clamp may be made; Fig. 3 is a plan view of the blade; Fig. 4 is a perspective view of the holder, opened to permit the insertion or removal of a blade; and Fig. 40 5 is a view partly in section of the holder with a blade clamped therein.

My razor blade holder comprises two parts—a frame or body member A; and a blade clamp B. The frame member A comprises a handle portion A' and a neck A² connecting the handle portion to the blade supporting portion A³. The blade supporting portion A³ is formed at its free edge with guard fingers A⁴, and at each end of 45 the bed or supporting surface for the blade with a lug or ear A⁵ and a lug or ear A⁶, which extend perpendicular to the bed or supporting surface. The double-edged blade C is formed with centrally disposed notches 50 C' in its ends, and with end surfaces C² at opposite sides of each notch C'. The blade 55

is so proportioned relative to the holder that when inserted in the latter the two end surfaces C² adjacent the then inactive or rear edge of the blade will fit snugly against the adjacent sides of the ears A⁶ thereby preventing the blade from movement in a direction parallel to its cutting edges. At the same time the ears A⁶ each fit snugly between the parallel sides of the corresponding notch C', and thereby prevent movement of the blade in a direction transverse to its cutting edge. The ears A⁶ are formed with apertures receiving the trunnion-like extensions B' formed on the plate clamping member B, which is thereby pivotally connected to the member A. The member B comprises a flat body portion, the free edge of which engages an inserted blade adjacent the active or front cutting edge of the latter, and an offset portion shown as consisting of two lugs B² which project to one side of the plane of the body portion of the clamping member and engage an inserted blade adjacent its rear or inactive edge. As the clamp is thrown from the open position shown in Fig. 4 into the closed position shown in Fig. 5, the free ends of the lugs B² will pass between the axis of the trunnions B' and the blade supporting surface A³, and the parts are so proportioned that the projections B² will be under tension when in the closed position shown in Fig. 5, and, in effect, form springs resiliently holding the clamping member B in the closed position.

It will be apparent without detailed explanation that the body member of my improved safety razor blade holder may be formed by simple manipulations out of the easily formed sheet metal blank a, shown in plan in Fig. 1. All that is required to convert the blank a into the holder body member A shown in Figs. 4 and 5, is to bend up the projecting portions forming the ears A⁵ and A⁶, slightly bend the guard fingers A⁴, 95 and offset the elongated tang of the blank to form the handle and neck portions A' and A². Advantageously though not necessarily, the handle portion A' is twisted into spiral form, as shown in Figs. 4 and 5. The clamp B may obviously be formed from the sheet metal blank b of Fig. 2, by simply bending the portions forming the spring projections B² away from the plane of the body portion of the clamp. It will be understood of course that in practice, the trunnions B' of the holder B will ordinarily

be inserted in the corresponding apertures in the ears A⁵ prior to giving the latter their final set perpendicular to the blade supporting surface A³.

5 Inasmuch as the inserted blade is held against movement parallel to its cutting edges by the engagement of the surfaces C² with the lugs A⁶, it is not essential that the lugs A⁶ should bear against the bottom of 10 the notches C', and the bottom edges C³ of these notches may therefore be rounded as shown. This is a matter of considerable practical importance where the blades are formed of highly tempered steel of ribbon-like thickness, since sharp corners, such as 15 it would be necessary to give the notches C' to make the latter fit snugly against the inner flat sides of the lugs A⁶ as well as against the edges of these lugs, are apt to 20 cause cracks in the blades in the tempering of the latter.

Having now described my invention, what I claim as new and desire to secure by Letters Patent, is:

25 1. A holder for a safety razor blade having notches formed in its ends, said holder comprising a frame member formed with a blade supporting bed and with an opposed pair of ears at the ends of the latter adapt-

ed to enter the notches in the ends of a blade 30 resting on said bed, and with a second opposed pair of ears at the ends of said bed adapted to engage the end surfaces of the inserted razor blade at one side of the notches thereof, and means for clamping a 35 razor blade against said bed.

2. In a safety razor, the combination of a blade having notches with rounded bottoms formed in its ends, and a blade holder 40 comprising a frame member formed with a bed on which the blade rests and with an opposed pair of ears entering the said notches and fitting between the sides thereof and thereby preventing movement of the blade in a direction transverse to its length 45 and formed also with a second pair of ears engaging the end surfaces of the blade at one side of the notches thereof and thereby preventing movement of the blade in a direction parallel to its length, the parts being so proportioned that the first mentioned 50 ears do not engage the rounded bottoms of the blade notches in which they enter.

DAVID M. PERINE.
